UNITED STATES PATENT OFFICE

2,573,502

MULTICHAMBERED GAS BURNER WITH
SELECTIVE GAS SUPPLYWilliam Smith, Jr., Dayton, Ohio, assignor to
General Motors Corporation, Dayton, Ohio, a
corporation of Delaware

Application May 23, 1945, Serial No. 595,389

4 Claims. (Cl. 158—105)

1

This invention relates to a domestic appliance and more particularly to gas burners and gas ranges.

It is an object of my invention to provide burner and control arrangements wherein the burner may be controlled to provide definite, readily set heat inputs so that cooking instructions may be more accurately followed.

It is another object of my invention to provide a burner and control arrangement of the multiple section type in which the lowest possible fuel input is accurately controlled and easily set, and progressively increasing fuel input is provided by progressively increasing the fuel input of each section in succession.

It is another object of my invention to provide a burner and control arrangement which is less likely to blow out at low heating rates.

It is another object of my invention to provide a burner and control arrangement which is at least as efficient at one-half maximum fuel input as at a maximum fuel input.

It is another object of my invention to provide a burner and control arrangement which has relatively high efficiency at low fuel inputs.

It is another object of my invention to provide a multiple section burner with a removable top on which the major portion of the machining operations are performed and which is so designed as to prevent fuel leakage without the use of gaskets.

It is another object of my invention to provide a multiple section burner arranged in such a way that the heating is substantially uniformly distributed when one of the sections is either completely out or on when another section is on.

It is another object of my invention to provide a burner wherein the main exposed joint is located adjacent the gas discharge opening so that if any leakage should occur through the joint the fuel issuing therefrom will be burned without any loss in efficiency.

It is another object of my invention to provide a burner of the multi-section type in which two sections provide a uniformly distributed discharge of fuel mixture in substantially the same direction into substantially the same area.

Briefly, to attain these objects I have provided a two-section annular burner with a removable flared top having drilled apertures extending from the inner section to the periphery and grooves extending from the outer section to the periphery substantially at the same angle. Each section is fed by a separate Venturi mixing tube cast as a unit with the two annular sections. The supply of fuel to the mixing tubes is con-

2

trolled by a single valve which first progressively increases the fuel supply to the outer section and then to the inner section. A saucer-shaped shield and a welded steel grid are also provided.

Further objects and advantages of the present invention will be apparent from the following description, reference being had to the accompanying drawing, wherein a preferred form of the present invention is clearly shown.

10 In the drawings:

Fig. 1 is a sectional view of a gas burner and control arrangement in a range;

Fig. 2 is a top view of the burner;

Fig. 3 is a sectional view taken along the line

15 3—3 of Fig. 1; and

Fig. 4 is a half sectional view of the removable burner top.

Referring now more particularly to Fig. 1, there is shown a gas range including a range top 20 having a flange 22 surrounding the burner opening. The burner has a unitary cast lower portion including two Venturi mixing tubes 24 and 26. The lower ends of the mixing tube castings are completely open making it possible to either make a very smooth interior in the casting or by machining the interior. The annular upper portion of the burner is provided with an outer annular wall 28 having a machined upper face, an inner annular wall 30 threaded on the inside and an intermediate annular wall 32 which is machined like the outer wall and divides the annular portion of the burner into an outer substantially annular passage or chamber 34 connecting to the mixing tube 24 and an inner substantially annular passage or chamber 36 connecting with the mixing tube 26.

The annular passages or chambers 34 and 36 are closed by a removable flared member 38 having its inner cylindrical portion 40 threaded into the inner wall 30 and its lower face provided with a flared machined surface which tightly fits the top of both the outer annular wall 28 and the intermediate substantially annular wall 32. The removable flared member is provided with uniformly distributed radial grooves 42 in the portion of its machined lower face extending between the outer substantially annular passage 34 and the peripheral wall 44 of the burner. These grooves 42 and the machined surface 46 as well as the flare of the member 38 are preferably at an angle of about 30 degrees from the horizontal. Four inwardly directed gas discharge passages 48 are also provided. These are drilled through the flared portion of the removable member 38 at an angle of about 30

degrees into the outer annular passage or chamber 34.

Between each of the grooves 42 in the flared member 38 are drilled gas discharge passages 50 which extend from a recess 52 in the flared member 38 forming a part of the inner substantially annular passage 36 to the peripheral wall 44 of the gas burner.

The gas burner is provided with two laterally extending support arms 54 and 55 supported in the recesses 56 and 58 provided in the flange 22 of the range top 20. The recess 56 is made of such a size to exactly receive the end of the supporting arm 54 which is made wider than the supporting arm 55 which is received within a narrower recess 58 so as to insure the proper orientation of the gas burner with respect to the range top.

A saucer-shaped shield 60 preferably provided with a turned down outer flange supported directly by the flange 22. The center of this shield 60 is provided with an opening which has its edges spaced away from the periphery of the burner a distance of about one-half inch at all positions. The edges of this opening are curled to make it more rigid and are slightly turned upwardly so as to catch a reasonable amount of spillage. This shield reflects the heat upwardly against the bottom of the utensils which are supported upon the grid 62. It also serves to control and guide the secondary air to promote combustion.

The non-breakable grid 62 is formed of a flanged inner ring 64. The ring 64 of steel to which is welded three or more substantially U-shaped members 66 of steel, having their surfaces at the same plane as the top of the flanged inner ring 64. The outer ring 68 of steel wire is welded to the bottom of the grid members 66. This keeps the grid 62 central with reference to the burner and prevents lateral bending of the grid members 66.

At the bottom of each of the mixing tubes 24 and 26 are the adjustable jets 70 and 72 commonly called spuds, which may be of the form shown in the Chambers Patent 2,162,374. To control the air-flow into each of the mixing tubes 24 and 26, each is provided with a sheet metal member. The sheet metal member 74 includes a disc portion having apertures therein for allowing air to enter the mixing tube 24 around the spud 70. To hold it in place the member 74 is provided with tongues extending outwardly from the disc portion which are bent upwardly over the flange provided by the bell-shaped mouth of the mixing tube 24. An adjustable shutter 76 is provided with registering apertures and is rotatably connected to the member 74 by the spun-over flanged ring 78 which slips over the spud 70. The shutter 76 is readily rotated and then locked in place by screw 80. The mixing tube 26 is similarly provided with a bell-shaped mouth provided with an apertured sheet metal disc member 82 and an identical adjustable shutter 84 having a set-screw 86.

The spud 70 is connected by the tubing 88 with the end connection 90 of the plug valve 92. The spud 72 is connected by the tubing 94 with the lateral outlet 96 of the valve 92. The valve 92 has a downwardly extending inlet 88 which connects directly with the supply manifold 121. The plug in the valve 92 is provided with a simmer passage 123 which, when the plug is turned to the position shown in Figs. 1 and 3, connects with a small passage provided along the axis of the plug into which extends a pin 124 provided

at the end of the adjusting screw 125. The simmer passage 123 connects the supply manifold 121 to the axial passages in the valve which connect to the outer passage 34. The screw 125 may be adjusted so that its pin 124 will close a portion of the discharge end of the simmer passage 123 in order to set accurately the amount of gas flowing to the burner when the operating dial 127 of the valve 92 is turned to the simmer position. By this arrangement the simmer can always be kept at the same value.

The valve plug is also provided with a cutout or another passage 129 which cuts out about $\frac{3}{8}$ of the middle portion of the plug. As will be evident from Fig. 3, as soon as the valve plug is turned in a counterclockwise direction and before the simmer passage is out of registration with the inlet connection 98 the passage 129 will begin to come into registration with the passage 98 to allow the flow of gas from the manifold 121 directly to the interior of the valve plug which connects to the outer annular passage 34. Further counterclockwise rotation of the operating valve 127 and the valve plug will provide increasing registration between the inlet 98 and the passage 129 to provide progressively increasing volumes of gas flow to the outer annular passage 34. All this time the lateral outlet 96 is shut off and no gas flows to the inner annular passage 36.

The supply of gas solely to the tube 88 and the spud 70 causes a jet of gas to discharge into the bell-shaped mouth of the Venturi mixing tube 24 causing air to be drawn in through the shutter arrangement into the bell-shaped mouth of the mixing tube 24 along with the gas in substantially the proper proportion. This gas flows directly upwardly and connects directly with the outer annular passage 34 providing a smooth flow of gas with a minimum of restriction. The gas is discharged from the outer annular passage 34 mainly through the grooves or first set of passages 42. Some gas, however, discharges from the four openings or second set of passages 48 in the interior of the burner so as to uniformly distribute the heat provided by the burning gas fuel. The flame from the gas discharge openings 42 and 48 increases from a tiny flame of about $\frac{1}{8}$ " long to a flame about 1" long.

Further increase in the heating arrangement is obtained by gradually turning passage 129 until it connects more and more with the lateral outlet 96. However, under such conditions the fuel supply to the outer annular passage and the discharge passages 42 and 48 is undiminished. The gas flowing through the side outlet 96 and the tubing 94 to the spud 72 draws in air through the shutter arrangement to the mixing tube 26 and supplies the combustible mixture to the inner annular passage 36. This gas is discharged through the drilled third set of passages 50 in gradually increasing amounts until at its maximum it provides substantially an equal amount of heat provided by the passages supplied from the outer burner section.

If it is not desired to use the two-burner sections progressively the operating knob 127 and the valve plug may be turned in a clockwise direction from the position shown in Figs. 1 and 3 and both burner sections will be supplied with gas simultaneously at an increasing rate. The complete off position will be between the position shown in Figs. 1 and 3 and the position in which the passage 129 is turned in a clockwise direction until it begins to register with the inlet

98. The valve may be arranged to be turned either or both directions from this "off" position as desired. If the knob 121 is turned in the clockwise direction from the "off" position to the "high" position, the passage 129 will first uncover the side outlet 96 and then will gradually register with the inlet 98 so that both burner sections will be simultaneously uniformly gradually lighted until the maximum rate is obtained. Further clockwise rotation will gradually reduce the fuel supply to the inner section without changing the supply to the outer section until the fuel supply to the inner section is entirely cut off. Further rotation in the clockwise direction will gradually reduce the fuel supply to the outer section until the simmer passage 123 remains as the sole avenue of fuel supply providing minimum heating.

To make it possible for the valve to be operated in these various ways the passage 129 should provide a span of about $\frac{3}{8}$ ", the circumference of the valve plug, while the simmer passage 123 should be located between $\frac{1}{8}$ and $1\frac{1}{4}$ the circumference of the valve plug beyond the passage 129.

For automatic lighting, the burner may be provided with a flash tube 131 into which discharges one drilled opening in the outer wall of the burner. The flash tube 131 connects with a pilot light not shown. To light the burner, the operating dial 127 is turned directly to the "high" position. This causes the lighting of the burner from the flash tube 131.

By employing two mixing tubes, each having a capacity for supplying one-half the burner, the variation in the air-fuel ratio from the lowest to the highest heating rate is reduced and the mixture control can be set to provide a more uniform air-fuel ratio which corresponds throughout the heating range more closely to the uniform air-fuel ratio required for greatest efficiency at all heating rates. The long straight, vertical, smooth mixing tubes further contribute to the more efficient mixing of the air and fuel since the gas fuel used is considerably lighter than air and provides a slight stack effect to aid in carrying the mixture through the mixing tubes.

While the form of embodiment of the invention as herein disclosed, constitutes a preferred form, it is to be understood that other forms might be adopted, as may come within the scope of the claims which follow.

What is claimed is as follows:

1. A burner comprising in combination, three ring-shaped walls arranged one within the other, an annular removable wall member disposed over and tightly engaging said ring-shaped walls and cooperating therewith to form two separated ring-shaped chambers, said annular removable wall member having a central opening providing an upflow air passage through said burner, a source of supply for a gas, means for separately conducting the gas from said supply source to the separated chambers, said outer ring-shaped wall and said removable wall member forming a first set of discharge passages communicating with the outermost ring-shaped chamber of the burner and extending outwardly to the periphery thereof, said removable wall member having a second set of discharge passages communicating with said outermost ring-shaped chamber of the burner and extending through said wall member in an upward angular direction relative to said first set of passages toward the air passage through said burner inwardly of the outlets of said first set of passages, said removable wall

member having a third set of discharge passages communicating with the innermost ring-shaped chamber and extending outwardly therethrough to the periphery of the burner and above said first set of passages, and means interposed between said supply source and said conducting means for selectively controlling flow of the gas to the separated chambers.

2. A burner comprising in combination, three
10 ring-shaped walls arranged one within the other,
an annular removable wall member disposed over
and tightly engaging said ring-shaped walls and
cooperating therewith to form two separated
15 ring-shaped chambers, said annular removable
wall member having a central opening providing
an upflow air passage through said burner,
a source of supply for a gas, means for separately
conducting the gas from said supply source to
20 the separated chambers, said outer ring-shaped
wall and said removable wall member forming
a first set of discharge passages communicating
with the outermost ring-shaped chamber of the
burner and extending outwardly to the periphery
25 thereof, said removable wall member having a
second set of discharge passages communicating
with said outermost ring-shaped chamber of
the burner and extending through said wall mem-
ber in an upward angular direction relative to
30 said first set of passages toward the air passage
through said burner inwardly of the outlets of
said first set of passages, said removable wall
member having a third set of discharge passages
communicating with the innermost ring-shaped
35 chamber and extending outwardly therethrough
to the periphery of the burner and above said
first set of passages, valve means interposed be-
tween said supply source and said conducting
means, said valve means being so constructed and
40 arranged as to provide a restricted flow of the
gas to said outermost chamber in a first position
thereof and when moved from said first position
into a second position progressively increasing
said flow to said outermost chamber, and the
construction and arrangement of said valve
45 means also being such that upon movement there-
of from said second position into a third position
flow of the gas is simultaneously directed
to said outermost chamber and to said innermost
chamber.

50 3. A burner comprising in combination, three
ring-shaped walls arranged one within the other,
an annular removable wall member disposed
over and tightly engaging said ring-shaped walls
55 and cooperating therewith to form two separated
ring-shaped chambers, said annular removable
wall member having a central opening providing
an upflow air passage through said burner, a source
of supply for a gas, means for separately
conducting the gas from said supply source
60 to the separated chambers, that portion of said
removable wall member engaging the outer wall
of the outermost chamber being provided with
a plurality of grooves, said grooves extending
continuously across said outer wall of the outer-
65 most chamber and cooperating therewith to pro-
vide a first set of discharge passages communicat-
ing with said outermost chamber and extending
to the periphery of the burner, said removable
wall member having spaced openings extending
70 in an upward direction therethrough toward the
air passage through said burner and inwardly
of the outlets of said first set of passages to pro-
vide a second set of discharge passages com-
municating with said outermost chamber, said
75 removable wall member having spaced apart

openings extending therethrough above and in a direction substantially paralleling said first set of passages to provide a third set of discharge passages communicating with the innermost chamber and extending outwardly to the periphery of said burner, and means interposed between said supply source and said conducting means for selectively controlling the flow of gas to the separated chambers.

4. A burner comprising in combination, three ring-shaped walls arranged one within the other, an annular removable wall member disposed over and tightly engaging said ring-shaped walls and cooperating therewith to form two separated ring-shaped chambers, said annular removable wall member having a central opening providing an upflow air passage through said burner, a source of supply for a gas, means for separately conducting the gas from said supply source to the separated chambers, that portion of said removable wall member engaging the outer wall of the outermost chamber being provided with a plurality of grooves, said grooves extending continuously across said outer wall of the outermost chamber and cooperating therewith to provide a first set of discharge passages communicating with said outermost chamber and extending to the periphery of the burner, said removable wall member having spaced openings extending in an upward direction therethrough toward the air passage through said burner and inwardly of the outlets of said first set of passages to provide a second set of discharge passages communicating with said outermost chamber, said removable wall member having spaced apart openings extending therethrough above and in a direction substantially paralleling said first set of passages to provide a third set of discharge passages communicating with the innermost chamber and ex-

tending outwardly to the periphery of said burner, valve means interposed between said supply source and said conducting means, said valve means being so constructed and arranged as to provide a restricted flow of the gas to said outermost chamber in a first position thereof and when moved from said first position into a second position progressively increasing said flow to said outermost chamber, and the construction and arrangement of said valve means also being such that upon movement thereof from said second position into a third position flow of the gas is simultaneously directed to said outermost chamber and to said innermost chamber.
